FOLDABLE IRONING BOARD ASSEMBLY

John E. Loar and Erma C. Loar, Paducah, Ky.

Application September 13, 1948, Serial No. 48,996

6 Claims. (Cl. 38—114)

1

This invention relates to an ironing board and more particularly has reference to a collapsible or folding type ironing board whereby the board in its folded condition forms a compact unit for either storage or transportation purposes.

We are cognizant of the fact that foldable ironing boards have been provided, but such boards have not been entirely satisfactory. The majority of these constructions, even in the collapsed state, have been relatively bulky, thereby making ease of transportation, as well as storage during non-use, a serious problem. Moreover, the means by which the ironing surface has been maintained above the base when the board is in use, and by which the ironing surface is moved into close proximity to the base for storage, has been comparatively complex in structural detail. This, of course, materially increases the cost of manufacture, thus making widespread use of the board prohibitive, and in addition raises the problem of maintenance costs, due to the large number of parts which are subject to damage, with the attendant problems of replacement or repair.

An important object of our invention is to provide a foldable ironing board, wherein the ironing surface is supported upon the base by means of a lazy tong assembly which is so constructed as to maintain the ironing surface rigidly supported by the base during the ironing process and yet will enable the ironing surface to assume a close relationship to the base when the board is not in use, thereby providing a compact unit capable of easy transportation or storage.

Another object of the invention is to provide an ironing board of the foldable type which in its folded condition may be easily housed within a carrying case for storage or transportation purposes.

Still another object of the present invention is to provide a foldable ironing board which includes few essential parts, which is capable of being readily and inexpensively manufactured and which is positive and efficient in operation.

To achieve these and other objects, the invention includes a base, a hinged ironing surface and a collapsible structure interconnecting the ironing surface and the base. The collapsible structure comprises a pair of spaced lazy tongs connected in parallel relationship to the ironing surface and the base so that the ironing surface may assume a position spaced above and rigidly supported with respect to the base or a position in close relationship to the base when the board is not being used. The lazy tong assem-

2

bly is so constructed and cooperates with complementary members of the ironing surface and base as to prevent collapsing of the board during use.

With the above and other objects in view, the invention consists in the details of construction, and in the arrangement and combination of parts to be hereinafter more fully set forth and claimed.

10 In describing our invention in detail, reference will be had to the accompanying drawings, forming part of the application, wherein like characters denote corresponding parts in the several views, and in which:

15 Figure 1 is a side elevational view of the board in the operative position.

Figure 2 is a view taken along the line 2—2 of Figure 1, looking in the direction of the arrows.

20 Figure 3 is an end view looking toward the left of Figure 1, the ironing surface and base being in section.

Figure 4 is a side elevational view of the board showing the parts preparatory to folding the board.

25 Figure 5 is an end view looking toward the right of Figure 4 showing the board in the folded state.

Figure 6 is a side view showing the board in the folded state.

30 Figure 7 is a view in front elevation, partly broken away, showing the folded board within a case; and

Figure 8 is a top plan view of the ironing board in the operative position, but being on a reduced scale.

35 In Figure 1, we have shown a base 10, an ironing surface 11 and a collapsible structure 12, connecting the base and ironing surface. The base is preferably rectangular in outline and of such dimensions as to provide a sturdy supporting surface for the ironing surface. The surface 11 is of the conventional design and includes a front section 11A and a rear section 11B, secured along their adjoining ends by a hinge 13. The leaves of the hinge are connected to the lower face of each of the sections 11A and 11B, so that the section 11A may be moved downwardly about the hinge 13 and thence upwardly into approximately parallel relation to the section 11B when the board is folded for storage purposes, as will later be more fully set forth. It can be seen from Figures 1 and 8 that a support 14 extends transversely of the section 11A intermediate the length thereof and is se-

cured to the lower face of the section in any suitable manner. The inner vertical wall of the support is formed with a longitudinally extending hemispherical recess 15 for receiving a brace element carried by the structure 12 to maintain the section 11A in horizontal alignment with the section 11B which structure will be hereinafter described.

The structure 12 comprises a pair of spaced parallel lazy tongs 13'. Each pair of lazy tongs 10 includes crossed links 14 and 15 pivotally connected intermediate the ends thereof, as shown at 16 and pivotally attached at the ends to the crossed links of an adjacent pair, as indicated at 17. Since the lazy tongs are in parallel relation, the pivots 16 and 17 are in the nature of rods which extend transversely of the board as shown in Figures 2 and 3.

The free end of the lowermost of each link 14 is hinged to the vertical wall of an L-shaped bracket, as at 19, which bracket is secured to the upper face of the base adjacent to the rear edge thereof. The free end of the uppermost link 15 of each pair of lazytongs is pivoted to a U-shaped bracket 20, supported by the lower face of the section 11B by means of a pin 21 extending through aligned openings in each link 15 and each bracket 20, and it can be seen that the brackets 18 and 20 are in vertical alignment. The free end of each uppermost link supports a rod 22 which is adapted to bear against the lower face of section 11B adjacent to hinge 13 when the structure 12 is in its extended position. As best shown in Figures 1 and 4, the free end of each of the lowermost links 15 also support a cross rod 23 which is adapted to set in a longitudinal recess 24 formed in the inner wall of a support 25 attached to the base 10 along and parallel to the front edge of the base.

Each lazy tong 13' supports a link 26 which is pivoted at its inner end on the pivot 17 at the outer extremity of the link 14 immediately below the uppermost link 15. The free end of each of the links 26 are connected by a cross piece 27 and the cross piece 27 is adapted to be received by the recess 15 of the support to maintain the section 11A in alignment with section 11B when the board is being used.

Assuming the board is in its collapsed state, as in Figure 6, when it is desired to use the board, the section 11B is moved upwardly, thereby moving the lazy tong sets to their extended position. The lowermost link 15 is then removed until the rod 23 engages the recess 24 in the support 25 and the links 14 and 15 will be kept in the extended position. The section 11A is then moved upwardly about the hinge 13 until it is in horizontal alignment with the section 11B and by locating the cross piece 27 in the recess 15, it can be seen that the sections 11A and 11B will be maintained in the desired relationship.

An ironing board pad and cover (not shown) may then be disposed on the ironing surface, and the board is now ready for use.

To fold the board, the links 26 are moved out of engagement with the recess 15 and the section 11A moved about the hinge 13 until, it assumes a substantially parallel position relative to the section 11B. The links 26 are then moved rearwardly about the pivot 17 into a nested position with respect to the uppermost link 15 and to assure a snug fit, each link 26 is cut away, as at 29 to receive the pivot member 16. The rod 23 is withdrawn from the recess 24 for enabling the lazy tong sets to fold, and the board may

now be collapsed to the position shown in Figures 5 and 6.

When the board is in the folded position, it may be disposed in lower half 30 of a carrying case 31, having a hinged cover or lid 32. If desired, the cover may carry a pocket 33 for a pressing cloth, a bracket 34 for holding a folding iron 35 and an electric extension cord 36. Any suitable latching means 37 may be employed to lock the carrying case.

It will be readily appreciated from the foregoing that we have provided a collapsible ironing board which in its folded state forms a very compact unit and which in the extended condition affords a sturdy assembly and there is little danger of the board collapsing during the ironing process. The board may be set up for use or folded for storage or transportation in a minimum of time and by virtue of the simple structural details may be easily operated by inexperienced persons.

We claim:

1. A foldable ironing board comprising a base, spaced lazy tongs pivotally connected at their inner lower ends to the base, an ironing surface, a pivotal connection between the ironing surface and the inner upper ends of the lazy tongs, complemental means carried by the base and the outer lower ends of the lazy tongs to maintain the lazy tongs in the extended position when it is desired to use the ironing board, and a bracing member pivotally attached to the lazy tongs intermediate the outer upper and lower ends thereof adapted to engage the ironing surface to stabilize the surface when said lazy tongs are in the extended position.

2. A foldable ironing board comprising a base, a pair of spaced lazy tongs pivotally attached at their inner lower ends to the base, an ironing surface having two hingedly connected sections, a pivotal attachment between one of said sections and the inner upper ends of the lazy tongs, complemental means carried by the outer lower ends of the lazy tongs and the base to maintain the lazy tongs in the extended position, and additional complemental means supported by said lazy tongs intermediate the upper and lower outer ends thereof and the other of said ironing sections to maintain said latter section in alignment with the first named section when the lazy tongs are in the extended position.

3. A foldable ironing board as claimed in claim 2 wherein a bracing member is pivotally attached to the lazy tongs intermediate the upper and lower outer ends thereof and adapted to engage the other of said sections to maintain said section in alignment with the first named section when the lazy tongs are in the extended position.

4. A foldable ironing board comprising a base, a pair of spaced parallel lazy tongs pivotally connected at the inner lower ends thereof to the base, a pair of ironing surfaces, a hinge connection between said surfaces whereby one of the surfaces may have downward pivotal movement relative to the other surface, a pivotal connection between the fixed surface and the upper inner ends of said lazy tongs, complemental means carried by the lower outer ends of the lazy tongs and the base for maintaining the lazy tongs in the extended position, and additional complemental means supported by the lazy tongs intermediate the upper and lower outer ends thereof and the movable surface to maintain said surface in alignment with the fixed surface when the lazy tongs are in the extended position.

5. A foldable ironing board as claimed in claim 4 wherein a bracing member is pivotally attached to said lazy tongs intermediate the upper and lower outer ends thereof and adapted to engage the movable surface to maintain said surface in alignment with the fixed surface when the lazy tongs are in the extended position.

6. A foldable ironing board comprising a base, a pair of lazy tongs pivotally attached at their lower inner ends to the base in parallel relation, 10 a stop secured to the base, a rod carried by the lower outer ends of the lazy tongs adapted to engage the stop to maintain the lazy tongs in the extended position, an ironing surface pivotally attached to the upper inner ends of the lazy tongs, 15 a complemental ironing surface hingedly attached to the first named surface for pivotal movement downwardly with respect thereto, a stop carried by the complemental surface, and a bracing

6 member pivotally attached to the lazy tongs intermediate the upper and lower outer ends thereof adapted to engage said last named stop and thereby maintain the complemental surface in alignment with the other surface when the lazy tongs are in the extended position.
